(57) **CLAIM**

The ornamental design for a baby seat as shown and described.

DESCRIPTION

FIG. 1 is a perspective view of the baby seat in a partial open configuration showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line showing of portions of the baby seat is included for the purpose of illustrating environmental structure and forms no part of the claimed design.
